CLAIM

The ornamental design for a picnic table, substantially as shown and described.

DESCRIPTION

FIG. 1 is a perspective view of a picnic table embodying my new design;

FIG. 2 is a top plan view of the picnic table;

FIG. 3 is a bottom view of the picnic table;

FIG. 4 is a side elevational view of the picnic table, the opposite side view being substantially identical thereto; and

FIG. 5 is an end elevational view of the picnic table, the opposite end view being substantially identical thereto.

Fig. 5.
